WALTER CROCKER, OF MEADVILLE, PENNSYLVANIA.

Letters Patent No. 75,737, dated March 24, 1868.

IMPROVEMENT IN UTERINE ABDOMINAL SUPPORTERS.

The Schedule referred to in these Letters Patent and making part of the same.

TO ALL WHOM IT MAY CONCERN:

Be it known that I, WALTER CROCKER, of the city of Meadville, in the county of Crawford, State of Pennsylvania, have invented a new and improved "Female Abdominal Uterine Supporter," which I verily believe has not been before known or used; and I do hereby declare that the following is a full and exact description of the same, reference being had to the accompanying drawings and the letters of reference marked thereon.

A A is a broad band, of double cloth or other suitable material, with whalebones C C C C C C C C, sewed transversely across it. B B are eyelet-holes, that the same may be laced around the abdomen immediately above the "pelvic" bones. D is a "pad," stuffed and quilted, and sewed on the band A A. This pad is placed over the "lumbar" region, and the ends of the band brought around in front and laced. E E are two "pads," attached to the band A A, dropping down in front immediately above the "pubic" bones, for the purpose of supporting the "abdominal muscles." m m are two short straps, with eyelets or buckles thereon. F F are two longer straps, with a connection of elastic cloth or rubber band, G G, attached to them, and on the ends thereof are two hooks, H H, to hook into the eyelets m m when eyelets are used. When the band A A is laced around the lower part of the abdomen the straps F F are passed between the thighs of the wearer each side of the "pro labia," and hooked or buckled to the straps m m. By this arrangement the abdominal muscles are supported by the pads E E, thereby sustaining the "uterus" in its natural or normal position.

What I claim as my invention, and desire to secure by Letters Patent, is as follows, to wit:

I claim the band A A and pad D, in combination with the pads E E and the straps F F and m m, when the same are constructed and arranged as described, for the purposes set forth.
